OF NEW YORK, N. Y., A CORPORATION OF NEW YORK.

DRAFT YOKE.

Application filed July 12, 1926. Serial No. 121,773.

This invention relates to improvements in draft yokes for railway cars, and more particularly to the construction of the rear end or stop thereof for engaging the adjacent 6 follower of the cushioning mechanism.

Draft yokes of the character referred to are subjected to very severe strains, the front and rear stops thereof being in particular subjected to great strain upon engagement 10 therewith of the adjacent followers of the cushioning mechanism interposed between the yoke and the car sills, the greater portion of this strain being concentrated at one side or the other of the stops when the car is 15 negotiating a curve, at which time the followers of the cushioning mechanism are tilted and engage only one side of the stops. While many and varied constructions of yokes have been proposed in which the stops thereof are 20 so reenforced that either side of the front or rear stop is liable to withstand the entire strain imposed thereon from the cushion mechanism, such constructions used heretofore have made necessary a substantial increase 25 in the weight of the yoke and, furthermore, have been objectionable for the reason that the reenforcing parts are so shaped that in casting the yoke shrinkage strains are developed whereby the casting is 30 weakened and tends to crack to materially reduce the efficiency and durability of the yoke.

One of the objects of the present invention, therefore, is to provide an improved draft yoke of the character referred to wherein the rear stop thereof is adequately reenforced so that in the event of tilting of the adjacent follower of the cushioning mechanism when the car is negotiating a turn the 40 strain due to the force concentrated at one side of the stop is distributed over the same, and to provide such a yoke which may be readily cast in one piece and without developing shrinkage strains, and which has advantages 45 over such yokes constructed heretofore as regards strength and ruggedness of construction, durability, weight, and cost of manufacture.

Other objects and advantages will herein- 50 after appear.

For the purpose of illustrating the invention one embodiment thereof is shown in the drawings, in which:

Figure 1 is a side elevational view;

Fig. 2 is a plan view; 55

Fig. 3 is a sectional view, taken on the line 3—3 in Fig. 1;

Fig. 4 is a sectional view, taken on the line 4—4 in Fig. 1; and

Fig. 5 is a sectional view, taken on the line 5—5 in Fig. 1.

The improved draft yoke comprises the upper and lower longitudinal draft bars 10 and 11 and the front and rear stops, designated generally in Fig. 1 by the reference numerals 12 and 13, respectively. As shown in Fig. 1, the respective rear ends, 14 and 15 of the draft bars 10 and 11 curve inwardly toward and merge together at the longitudinal axis of the yoke, these ends decreasing gradually in width rearwardly of the yoke, as shown in Fig. 2.

The rear stop 13 comprises the plate 16 arranged transversely of bars 10 and 11 and formed integrally at its ends with the latter 75 at the points 17 and 18, the plate being spaced from the bar ends 14 and 15, and a conically-shaped reenforcing portion or member 19 disposed between plate 16 and the bar ends and merging therewith at its ends, 80 the portion or member 19 being arranged with its longitudinal axis coincident with the longitudinal axis of the yoke, as shown. The end of portion 19 of larger cross-sectional area merges into and is formed or cast integrally with plate 16, while the other end of portion 19 of smaller cross-sectional area merges into and is formed or cast integral- 85 ly with the bar ends 14 and 15 substantially at their point of meeting on the longitudinal axis of the yoke. The re-enforcing portion or member 19 is made hollow, to provide therein the recess 20, the plate 16 and the bar ends 14 and 15 being provided with the openings 21 and 22 to permit of ready removal of the core used in the casting of the yoke to provide recess 20, the openings 21 and 22 also making for lightness of construction. The recess 20 formed in reenforcing portion 19 makes for lightness of construction without detracting from the strength of portion 19 beyond an amount entirely adequate to withstand any strains sustained in 90 actual use of the yoke.

Reenforcing webs 23 and 24 are disposed on opposite sides of the reenforcing portion 19 and are arranged in the vertical plane passing through the respective longitudinal 100 105

axes of the yoke and portion 19, these webs merging with and being formed integrally at their respective edges with plate 16, the bar ends 14 and 15, and portion 19, as shown. 45

5 The forward or front end of the yoke shown is of standard and well known construction, and comprises the vertically disposed spaced side cheeks 25 and 26 cast integrally with and connecting the adjacent 10 front ends 27 and 28 of bars 10 and 11, the respective rear edges 29 and 30 of cheeks 25 and 26 providing a stop for engagement with the adjacent follower (not shown) of the usual cushion mechanism interposed between the yoke and car sills. The spaced cheeks 25 and 26 receive the butt of the coupler shank (not shown), in the well known manner, and are provided with the longitudinal slots 31 and 32 for receiving the usual 15 retaining key for holding the coupler and yoke in assembled relation.

From the foregoing it will be seen that a draft yoke has been provided which is comparatively light and which has a rear end construction which is adequately reinforced to withstand the severe strains imparted thereto from the adjacent follower of the cushion mechanism, and that the conically-shaped reinforcing portion 19, as well as the webs 23 and 24, provide for very rigid construction and act to distribute the strain uniformly from one side of the rear stop 13 to the other side thereof upon tilting of the adjacent follower of the cushioning mechanism when the car negotiates a curve, and that the construction shown and described may be readily cast and is not susceptible to the shrinkage strains present in the various types of draft yokes constructed heretofore. 30

40 While but one embodiment of the invention has been shown and described, of course various changes may be made such as in the size and proportion of the parts without de-

parting from the spirit of the invention or the scope of the claims.

The invention claimed is:

1. A draft yoke comprising upper and lower longitudinal bars having their respective ends curved inwardly toward and merging at the longitudinal axis of said yoke, and a rear stop comprising a plate arranged transversely of said bars and connected at its ends to the latter and spaced from the bar ends, and a conically-shaped reinforcing portion disposed between said plate and the bar ends and merging at its ends with the latter and arranged with its longitudinal axis substantially coincident with the longitudinal axis of said yoke. 50

2. A draft yoke comprising upper and lower longitudinal bars having their respective ends curved inwardly toward and merging at the longitudinal axis of said yoke, and a rear stop comprising a plate arranged transversely of said bars and formed integrally at its ends with the latter and spaced from the bar ends, a conically-shaped reinforcing portion disposed between said plate and the bar ends and arranged with its longitudinal axis substantially coincident with the longitudinal axis of said yoke, the end of said portion of larger cross-sectional area merging with and being formed integrally with said plate, the opposite end of said portion of smaller cross-sectional area merging with and being formed integrally with said bar ends, and reinforcing webs disposed on opposite sides of said portion in a vertical plane through the longitudinal axes of said yoke and said portion and merging with and being formed integrally at their respective edges with said portion and the bar ends and the adjacent face of said plate. 65

In witness whereof, I hereto affix my signature.

LEO GRANT SULLIVAN.
